UNITED STATES PATENT OFFICE.

ALFRED M. LANE, OF ST. LOUIS, MISSOURI, ASSIGNOR TO MONARCH METAL PRODUCTS COMPANY, OF ST. LOUIS, MISSOURI, A CORPORATION OF MISSOURI.

WEATHER-STRIPPED METAL WINDOW.

Application filed April 11, 1927. Serial No. 182,561.

This invention relates principally to metal windows equipped with sashes slidable in guide slots provided therefor in the hollow jambs of the window frame, and it relates 5 more particularly to the application of metal weatherstrips to said windows.

The principal object of the present invention is to provide simple and efficient weatherstripping, which will prevent air and dust 10 from entering the room through the joints and slotted jamb members of the above type of metal window and which can be easily and cheaply applied without any alteration of the frame or sashes. Other objects are 15 to prevent rattling of the sashes without interfering with the easy movement thereof and to maintain a weatherproof construction in all positions of the sliding sashes.

The invention consists principally in the 20 novel construction, arrangement and application of weatherstripping; and it also consists in the parts and in the arrangements and combinations of parts hereinafter described and claimed.

25 In the accompanying drawings, which form part of this specification and wherein like symbols refer to like parts wherever they occur,

Fig. 1 is a vertical cross section through 30 a metal window construction equipped with metal weatherstripping embodying my invention;

Fig. 2 is a horizontal section through one 35 side of the window frame and the adjacent portion of the upper sash on the line 2—2 in Fig. 1; and

Fig. 3 is a similar cross section through one 40 of the jambs of the window casing and the adjacent side rail of the lower sash on the line 3—3 in Fig. 1.

In the accompanying drawings, my invention is illustrated in connection with a metal window of the double-hung sliding-sash type, said window comprising a metal window 45 frame or casing member A arranged for vertically sliding upper and lower metal closure members or sashes B and C, respectively. The metal window frame or casing A shown in the drawings comprises a hollow 50 head or lintel box 4, a sill 5, and two hollow or tubular jambs 6, one only of which is shown. As shown in the drawings, the parts of the hollow jambs 6 are arranged to form enclosed boxes for the sash weights and 55 chains (not shown); and the opposing inner

walls of the hollow jambs are each provided with two vertical guide slots 7 and 8, which extend from head to sill of the window frame or casing and constitute slideways for the upper and lower sashes, respectively. 60

The upper and lower sashes comprise main frame members 9, which are offset to form rabbets for supporting the marginal edges of the sash panes 10, and retaining strips 11 secured to said main frame members to hold said panes therein.

As shown in the drawings, the vertical frame members, which form the side rails of the upper or outer sash B, have their outer flanges 9^a slidably arranged in the outer guide 70 slots 7 provided in the inner or opposing walls of the hollow jambs 6. The upper flange 9^b of the main frame member, which forms the top rail of the said sash, projects within a downwardly opening slot or groove 75 4^a in the bottom of the lintel box 4 in the closed position of the sash; and the retaining strip which cooperates with said main frame member is provided with a stop shoulder 11^a adapted to abut against the under 80 side of the lintel box in the closed position of said sash. The retaining strip on the lower or meeting rail of the upper sash is preferably provided along its lower inner edge with an upstanding hook flange 11^b. 85

The vertical frame members, which form the side rails of the lower or inner sash C, have outstanding vertical side flanges 9^c slidably arranged in the vertical slots or 90 slideways 8 provided therefor in the opposing faces of the hollow jamb members 6. The retaining member on the upper or meeting rail edge of the lower sash C is shown provided along its upper outer edge with a depending hook flange 11^c adapted 95 to overlap the upstanding hook flange 11^b of the lower or meeting rail of the upper sash B in the closed positions of said sashes.

As shown in the drawings, blocks 6^a are secured to the inner faces of the hollow jambs 100 6, between the guide slots 7 and 8 thereof, in position to close the joints between said jambs and the ends of the meeting rails of the sashes in the closed positions thereof. The framing member, which forms the bottom rail of the lower sash C, is arranged with 105 its bottom flange 9^d in position to cooperate with the sloping outer side of an upstanding rib 5^a on the sill member 5 of the window frame A; and retaining strip for said bottom 110

rail of said lower sash C has an outstanding flange 11^a, which terminates in a depending lip adapted, in the closed position of said sash, to seat within an upwardly opening groove or channel 5^b provided therefor in the stool portion of said sill.

- In order to prevent air and dust from entering the building through the guide slots 7 and 8 in the hollow jamb member 6 of 10 the window, said jamb members are provided with metal weatherstrips 12, 13 and 14. As shown in the drawings, the weatherstrips 12 preferably extend from the sill 5 to the lower edges of the filler blocks 6^a and are 15 adapted to completely close the lower, normally unoccupied, portions of the guide slots 7 for the upper sash B. The weatherstrips 13 extend from the upper ends of the strips 12 to the underside of the lintel 20 box 4 and serve to weatherproof the joint between the upper portion of the outer guide slot 7 and the guide or runner flanges 9^a of the upper sash B in the closed position thereof. The strips 14 are secured to the 25 jamb members 6 adjacent to the outer face of the lower sash C and extend from the sill 5 to the under side of the filler blocks 6 and serve to weatherproof the joints between the lower portion of the inner guide slots 8 30 and the runner or guide flanges 9^c of the lower sash C in the closed position thereof. By this arrangement, the strips 12 and 13 serve to prevent air and dust from entering the hollow jambs 6 through the guide slots 7 35 for the upper sash B; and the strips 14 serve to prevent air and dust from entering the building through the joints between the lower sash C and the portion of the guide slots 8 normally occupied thereby.
- 40 Each of the weatherstrips 12 is provided along its middle portion with a longitudinal channel 12^a, which snugly fits the lower, normally unoccupied, portion of the outer guide slot 7, and outstanding side marginal flanges 12^b, which bear against the jamb 6 on opposite sides of said outer guide slot. As shown in the drawings, the channel 12^a is of a width adapted to accommodate the runner or guide flanges 9^a of the upper sash B when the same 45 is lowered; and the side marginal flanges 12^b of said strip are preferably provided with corrugations 12^c where they join the side walls of the channel 12^a to prevent binding or cutting of the strip on the sides of the slot. As shown in the drawing, the side 50 flanges of the strip 12 are provided adjacent to the corrugations 12^c with reversely corrugated portions 12^d adapted to bear against the jamb; and the free marginal edge of the 55 outer flange of said strip is provided with a hollow bead 12^e, the corrugations 12^c and 12^d and the bead 12^e permitting the flanges of the strip to be clamped tightly against the jamb to secure a weatherproof joint between 60 the jamb and the strip.

Each of the metal weatherstrips 13 preferably comprises a metal strip of substantially angular cross-section, one flange 13^a of which is rigidly secured to the jamb; and the other flange 13^b extends into the outer 70 guide slot 7 and constitutes a resilient sealing member which bears against the adjacent face of the guide flanges 9^a of the upper sash in the closed position thereof and thus serves to weatherproof the joint between said flange and said slot. The flange 13^a of the strip 13 is longitudinally corrugated as at 75 13^c, where it joins the resilient sealing flange 13^b, thereby preventing binding or cutting of the strip on the edge of the slot. The flange 13^a is also provided adjacent to the corrugation 13^c with a reversely corrugated portion 13^d, and has a curled marginal edge 13^e, whereby said flange may be pressed 80 tightly against the face of the jamb. 85

The strip 14 for closing the joint between the guide flanges 9^c of the lower sash C and the portion of the guide slots 8 normally occupied thereby are secured to the jambs 6 adjacent to the outer face of said sash. 90 Each of the strips 14 is of angular cross-section, one flange 14^a being secured to the jamb; and the other flange 14^b being left free and extending into the guide slot 8 in position to resiliently engage the guide flange 9^c 95 of the lower sash. As shown in the drawings, the flange 14^a, which is secured to the jamb, is reversely corrugated, as at 14^c, to secure a tight joint between said flange and the jamb and to prevent cutting or binding of the resilient sealing flange 14^b on the edge 100 of the guide slot 8.

The outer marginal flange 12^a of a strip 12 is secured to a jamb 6 preferably by means of a rigid clamping bar or strip 15 that is held 105 in position by means of screws 16, which pass through said flange and said clamping bar and are threaded into the jamb. The clamping bar or strip 15 has the same cross-sectional shape as the flange engaged thereby. The corrugated inner marginal flange 12^a of a strip 12 and the corrugated flange 14^a of a strip 14 are rigidly clamped to a jamb by means of a rigid clamping bar or strip 17, which is secured to said jamb by 110 screws 17^a, and has its side marginal portions shaped to snugly fit the corrugated flanges engaged thereby. Each of the strips 13 is clamped to a jamb by means of a rigid clamping strip 18, which is secured to said jamb by screws 19 and has the same cross-sectional shape as the flange against which it bears. The rigid clamping bars or strips 115 serve also as guard or wear plates to prevent the thin gage weather-strips engaged thereby from being crushed or otherwise damaged.

The joint between the top rail of the upper sash B and the guide slots occupied thereby in the raised position of said sash is 120

weatherproofed preferably by means of a strip 20 of substantially the same cross-sectional shape as jamb strips 13, and is secured in position by means of a clamping strip 21 similar to the clamping bar 18 used to secure the strip 13 in place.

The joint between the meeting rails of the upper and lower sashes is weatherproofed preferably by means of a metal weather-strip 22 secured to the hook flange 11^b of the meeting rail of the upper sash B. As shown in the drawing, said strip comprises a main body portion of angle shape section provided with a rebent resilient sealing flange 22^a adapted to bear against the depending hook flange 11^c on the meeting rail of the lower sash C in the closed position of the two sashes.

The weatherstrip 23 for the joint between the bottom rail of the lower sash C and the sill 5 of the window frame A comprises a strip of metal secured along one edge to the top of the upstanding rib 5^a of said sill 5 and a downwardly extending resilient free marginal portion adapted to be engaged by the lower flange 9^a of the bottom rail of the lower sash in its closed position.

The arrangement hereinbefore described has numerous advantages. It minimizes the time and expense of applying the strips by eliminating the need for altering the sashes or frame and by enabling the strips to be readily applied with a minimum number of fasteners. It prevents rattling of the sashes without interfering with the easy movement thereof; and it remains weatherproof and dust-proof in all positions of movement of the sashes and when the sashes are frame expand or contract due to temperature changes.

Obviously, the construction hereinbefore described admits of considerable modification without departing from the invention; therefore, I do not wish to be limited to the precise arrangement shown and described.

What I claim is:

1. The combination with a window comprising upper and lower sliding sashes and jamb members provided with guide slots in which said sashes slide, of weatherproofing means for the joints between the upper sash and the portions of the guide slots normally occupied thereby and for the normally unoccupied portions of said last mentioned guide slots.

2. The combination with a window comprising upper and lower sliding sashes and hollow jambs provided with vertical guide slots in which said sashes slide, of weatherproofing means for the joints between the upper sash and the portions of the guide slots normally occupied thereby and for the normally unoccupied portions of said last mentioned guide slots, the weatherproofing means for the normally unoccupied portions

of the guide slots for the upper sash being adapted to permit sliding movement of said sash in the normally unoccupied portions of the guide slots therefor.

3. The combination with a window comprising upper and lower sliding sashes and hollow jambs provided with vertical guide slots in which said sashes slide, of weatherproofing means for the joints between the lower sash and the portions of the guide slots normally occupied thereby, for the upper sash and the portions of the guide slots normally occupied thereby, and for the normally unoccupied portions of the guide slots for said upper sash.

4. The combination with a window comprising upper and lower sliding sashes and hollow jambs provided with vertical guide slots in which said sashes slide, of weatherproofing means for the joints between the upper sash and the portions of the guide slots normally occupied thereby and for the normally unoccupied portions of said last mentioned guide slots, said weatherproofing means comprising metal weatherstrips secured to said jambs, said strips having portions which close the normally unoccupied portions of the guide slots for the upper sash and resilient sealing flanges extending into the guide slots for the upper sash in position to bear against the portions of the sash slideable therein.

5. The combination with a window comprising upper and lower sliding sashes and hollow jambs provided with vertical guide slots in which said sashes slide, of weatherproofing means for the joints between the upper sash and the portions of the guide slots normally occupied thereby and for the normally unoccupied portions of said last mentioned guide slots, said weatherproofing means comprising resilient metal weatherstrips secured to said jambs, said strips having portions which close the normally unoccupied portions of the guide slots for the upper sash and resilient sealing flanges extending into the guide slots for the upper sash in position to bear against the portions of the sash slideable therein, and means for clamping said strips to said jambs.

6. The combination with a window comprising upper and lower sliding sashes and hollow jambs provided with vertical guide slots in which said sashes slide, of weatherproofing means for the joints between the upper sash and the portions of the guide slots normally occupied thereby and for the normally unoccupied portions of said last mentioned guide slots, said weatherproofing means comprising resilient metal weatherstrips secured to said jambs, said strips having portions which close the normally unoccupied portions of the guide slots for the upper sash and resilient sealing flanges extending into the guide slots for the upper

sash in position to bear against the portions of the sash slidable therein, and metal clamping strips for securing said weatherstrips to said jambs, said clamping strips constituting guard members for the portions of the strips engaged thereby.

7. The combination with a window comprising upper and lower sashes and hollow jamb members provided with guide slots 10 in which said sashes slide, of metal weatherstrips secured to said jambs for weatherproofing the joints between the upper sash and the portions of the guide slots normally occupied thereby and for weatherproofing 15 the normally unoccupied portions of the guide slots for said upper sash.

8. The combination with a window comprising upper and lower sliding sashes and hollow jamb members provided with guide 20 slots in which said sashes slide, of metal weatherstrips secured to said jambs for weatherproofing the joints between the upper and lower sashes and the portions of the guide slots normally occupied thereby and 25 for weatherproofing the normally unoccupied portions of the guide slots for said upper sash.

9. The combination with a window comprising upper and lower sliding sashes and 30 hollow jamb members provided with guide slots in which said sashes slide, of metal weatherstrips for weatherproofing the joints between the upper and lower sashes and the portions of the guide slots normally occupied 35 thereby and for weatherproofing the normally unoccupied portions of the guide slots for said upper sash, and clamping strips for securing said strips to the jambs.

10. The combination with a window comprising hollow jambs provided with vertical 40 guide slots and upper and lower sashes having side flanges slidable in said guide slots, of metal weatherstrips secured to said jambs and having resilient sealing flanges extending 45 into the slots for the upper sash in position to bear against the guide flanges of said sash in the closed position thereof and having portions adapted to close the normally unoccupied portions of the slots 50 for said upper sash.

11. The combination with a window comprising hollow jambs provided with vertical 55 guide slots and upper and lower sashes having side flanges slidable in said slots, of weatherstrips secured to said jambs and having resilient sealing flanges extending into the slots for the upper and lower sashes in position to bear against the guide flanges of said sashes in the closed positions thereof 60 and portions adapted to close the normally unoccupied portions of the slots for said upper sash.

12. The combination with a window comprising hollow jambs provided with vertical 65 guide slots and upper and lower sashes having side flanges slidable in said guide slots, of metal weatherstrips secured to said jambs and having resilient sealing flanges extending into the slots for the upper sash in position to bear against the guide flanges of said 70 sash in the closed position thereof and having portions adapted to close the normally unoccupied portions of the slots for said upper sash, said slot closing portions being shaped and arranged to permit sliding 75 movement of the guide flanges of the upper sash in the lower portions of the slots therefor.

13. The combination with a window comprising a sliding sash and jamb members 80 provided with guide slots in which said sash slides, of weatherproofing means for said guide slots, said weatherproofing means comprising metal weatherstrips secured to said jambs and having substantially channel-shaped portions fitting said guide slots.

14. The combination with a window comprising a sash and hollow jambs provided with vertical guide slots in which said sash slides, of weatherproofing means for said 90 guide slots, said weatherproofing means comprising metal weatherstrips having substantially channel-shaped body portions located within said slots and side marginal flanges secured to said jambs on opposite sides of 95 said slots.

15. The combination with a window comprising a sash and hollow jambs provided with vertical guide slots in which said sash slides, of weatherproofing means for said 100 guide slots, said weatherproofing means comprising metal weatherstrips having substantially channel-shaped body portions located within said slots and side marginal flanges secured to said jambs on opposite sides of 105 said slots, said flanges being longitudinally corrugated adjacent to said channel.

16. The combination with a window comprising hollow jambs provided with vertical 110 guide slots and upper and lower sashes having side flanges slidable in said guide slots, of metal weatherstrips secured to said jambs and having resilient sealing flanges extending 115 into the slots for the upper sash in position to bear against the guide flanges of said sash in the closed position thereof and having portions adapted to close the normally unoccupied portions of the slots for said upper sash, the portions of said strip located adjacent to said slots being longitudinally 120 corrugated.

Signed at St. Louis, Missouri, this 8th day of April, 1927.

ALFRED M. LANE.
